FENDER SIGNAL LAMP FOR AUTOMOBILES

Jesse R. Hollins, Brooklyn, N. Y.

Application September 14, 1953, Serial No. 26,787

Term of patent 14 years

(Cl. D48—33)

To all whom it may concern:

Be it known that I, Jesse R. Hollins, a citizen of the United States, residing at 4144 Kings Highway, in the Borough of Brooklyn, county of Kings, and State of New York, have invented a new, original, and ornamental Design for a Fender Signal Lamp for Automobiles, of which the following is a specification, reference being had to the accompanying drawing forming a part hereof, in which:

Fig. 1 is a side elevational view of a fender signal lamp for automobiles showing my new design;

Fig. 2 is a front elevational view thereof;

Fig. 3 is a rear elevational view; and

Fig. 4 is a side elevational view to a smaller scale.

The dotted lines shown in the drawing are for illustrative purposes only.

I claim:

The ornamental design for a fender signal lamp for automobiles, as shown and described.
